The ornamental design for a scrub brush handle, as shown and described.

DESCRIPTION

FIG. 1 is a front, top, left perspective view of the scrub brush handle embodying my new design;

FIG. 2 is a top plan view thereof;

FIG. 3 is a right side elevational view thereof;

FIG. 4 is a front elevational view thereof;

FIG. 5 is a rear elevational view thereof; and,

FIG. 6 is a bottom plan view thereof.

The left side elevational view is not shown but is the mirror image of the right side elevational view shown in FIG. 3.

The broken line showing of bristles is for illustrative purposes only and forms no part of the claimed design.
